UNITED STATES PATENT OFFICE.

WILLIAM S. McADOO, OF CHICAGO, ILLINOIS.

COMBINATION-PADLOCK.

1,383,317.

Specification of Letters Patent. Patented July 5, 1921.

Application filed August 2, 1920. Serial No. 400,724.

To all whom it may concern:

Be it known that I, WILLIAM S. McAdoo, a citizen of the United States, and a resident of the city of Chicago, in the county of Cook 5 and State of Illinois, have invented a new and useful Improvement in Combination-Padlocks, of which the following is a full, clear, and exact description.

My invention relates to improvements in 10 padlocks which may be opened by setting particular combinations, and it consists in the constructions and arrangements herein described and claimed.

Combination padlocks have been used in 15 which number wheels may be set to effect the opening of the lock, but in most instances, these number wheels are exposed in such position that a blow from a heavy instrument, such as a hammer, wrench, etc., on the number 20 wheels will put them out of commission.

Certain locks of this type have parts 25 which project from the barrel which may afford a means of attachment for a pipe wrench or other tool, so that the parts may be sometimes twisted off, thus ruining the lock.

In other instances, there are openings in the lock which will permit a tool to enter which can be easily put out of commission by 30 driving the tool in.

An object of the present invention is to provide a padlock having a shackle which is held positively by a removable pin and which is provided with character bearing 35 wheels or rings that are countersunk, so as to prevent the injury to the wheels by a blow from a hammer or the like.

A further object is to provide a lock of 40 the type described, in which there are no projecting parts or openings that may permit the use of tools to put the lock out of commission.

A further object of my invention is to provide a lock in which the wheels or rings 45 bearing characters are spaced apart so that the manipulation of one ring will not disturb the setting of another ring.

A further object of my invention is to provide a device of the type described in which 50 there is no danger of disturbing the relative arrangement of the rings when the device is unlocked, as, for instance, by dropping it on the ground.

A further object of the invention is to pro-

vide a device having a protective casing 55 which forms a reinforcement of the barrel or body portion and a covering for the character bearing wheels or rings, said casing being easily removed when the device is unlocked, and being securely held in position 60 when the device is locked.

A further object of my invention is to provide a slidable guard or shield so as to prevent water from getting into the interior of the lock, said shield being shiftable to permit ready access to the character bearing 65 rings so as to permit the shifting of the latter and the setting of the proper combinations to unlock the device.

Other objects and advantages will appear 70 in the following specification, and the novel features of the invention will be particularly pointed out in the appended claims.

My invention is illustrated in the accompanying drawings, forming part of this application, in which—

Figure 1 is a side view of the lock in closed position,

Fig. 2 is an end view thereof,

Fig. 3 is a central longitudinal section, 80

Fig. 4 is a section along the line 4—4 of Fig. 3, and

Fig. 5 is a side view of the pin or keeper.

In carrying out my invention, I provide a barrel or body portion 1 which is substantially cylindrical in shape and which has an extension 1_x, as shown in the drawings. The body portion 1 is provided with a central cylindrical bore 2 extending from end to end. Transversely extending slots 3 are provided 85 in the body portion or barrel 1, these slots being spaced equally distant and extending well into the extension 1_x, as shown in Figs. 3 and 4. There is also a longitudinal slot 4 contiguous to and running parallel with the central bore 2. This slot terminates, however, short of one end, as will be seen in Fig. 3. Disposed in the central bore is a bushing 5 which has a closed end 6 and which is provided with a longitudinal slot 7. The closed 90 end 6 has its outer surface flush with the end of the body portion 6, and the slot 7 is in registration with the slot 4 in the body portion or barrel. Disposed in each of the slots is a ring or wheel 8 bearing characters, such 95 as letters or figures, on the periphery thereof (see Fig. 1). Each ring is provided with a series of transverse notches 10 for a purpose

hereinafter explained. It will be observed that the rings are mounted for revolution on the bushing (see Fig. 4), and that they are countersunk beneath the exterior of the body portion 1.

On the exterior of the body portion is a reinforcing casing 11. The exterior of this casing is substantially cylindrical, but it has a slot arranged to receive the extension 1_x 10 of the body portion, and it may be slipped over the body portion in the manner shown in the drawings. A case hardened shackle 12 is provided, the ends 12_a of the shackle being preferably reduced and flattened, so as 15 to enter alined openings in the casing, the body portion, and the bushing. The ends 12_a are provided with openings 13 arranged to receive a pin or keeper 14 of the shape shown in Fig. 5. The latter is provided with a head 20 14_a arranged to enter a recessed portion of the barrel 1. The pin 14 is provided with a key or feather 15 adapted to enter the alined slots 7 and 4, and also to enter slots 16 in each of the wheels or rings 8 when the latter are 25 in position, so that the slots 16 are in alinement. The key 15 is provided with slots 17 arranged to receive the rings 8. As will be seen from Fig. 4, the casing 11 is provided with a slot 18, through which the rings or 30 wheels may be viewed. At the edge of the slot is a plate 19 which is countersunk in the casing, and is secured thereto, and is provided with inwardly extending fingers 20 which are arranged to engage in the slots 10 35 in the rings.

An exterior guard or shield 21 is provided, this shield being curved to conform with the curvature of the casing 11, a portion of the shield being struck up to provide a handle 40 22, thereby leaving a slot 23 which may be brought into registration with the slot 18.

Between the adjacent wheels or rings is a spiral spring 24 which exerts friction on the ring so as to prevent undue movement, as 45 will be explained later.

From the foregoing description of the various parts of the device, the operation thereof may be readily understood. In assembling the device, the ring at the left of Fig. 50 3 is first placed in its slot and then the spring 24 is pushed into position through an opening or passage 25 extending inwardly from one end. The remaining rings and springs are placed successively, and the end of the 55 passage 25 is closed by a pin or bar 26. The bushing 5 is then placed in position and the casing 11 is slipped on, so that the openings in the bushing, the casing, and the barrel are in registration to receive the ends 12_a of the 60 shackle.

When it is desired to use the lock, the shackle is slipped through the eye or staple which is designed to be locked, and its ends are passed into the alined openings, and then

the pin 14 is placed in position, the slots 16 65 of the rings 8 being previously placed in alinement. Any of the rings may now be turned, preferably by inserting a pointed tool in the alined slots 23 and 18 (see Fig. 4), the end of the tool entering one of the small 70 slots 10, so that by exerting pressure in either direction, the wheel is turned, the members 20 acting as clicks, so as to enable one to bring the rings into predetermined positions.

The lock cannot be opened until the slots 75 16 in the rings 8 are again brought into alinement. This, of course, can only be done by one knowing the proper combination of characters of the periphery of the rings. When the lock is opened, the pin is removed and 80 the shackle will then be free to be withdrawn. The barrel and its casing may be jolted or jarred, as in throwing it on the ground, without any danger of the rings moving out of position to permit the reinsertion of the pin, 85 partly on account of the springs 24 which tend to hold the rings in fixed position, and partly on account of the clicks 20 which engage the slots in the rings.

The clicks 20, however, have another function, because they enable one to open the lock in the dark. All that is necessary is to remember how many notches the wheels have been turned out of alinement, and to turn them either backwardly or forwardly the 95 necessary distance, counting the clicks. Thus without seeing the characters the lock may be opened by one who knows how far the wheels have been previously turned.

The guard 21 may be moved so as to completely cover the opening 18, thus preventing the entrance of water and consequently decreasing the chances of the interior becoming rusty or corroded.

It will be observed that there are no projections beyond the ends of the barrel or its reinforcing casing which may be grasped by a pipe wrench, and that the rings are not only below the surface of the reinforcing casing, but they are countersunk below the 105 barrel itself. It is not easy, therefore, to put the lock out of commission by a blow from a hammer, since the hammer cannot reach the rings. In certain devices of the type, it is comparatively easy to shear off the pivot pin of the shackle, but in the present instance, there is no pivot pin, and since the shackle and the reinforcing casing are case hardened, it is a very difficult matter to put the lock out of commission. It will also 110 be observed that there are no screw bolts or rivets in the construction of the lock.

If for any reason it is desired to change the combination, it may be done very easily by unlocking the device and removing the 125 reinforcing casing and the bushing and interchanging the rings. If it should happen that moisture should collect in the interior,

it will drain out through the small passages 27 which lead to the extension 1_x, thus keeping the lock comparatively dry.

I claim:

- 5 1. A combination padlock comprising a body portion or barrel having a central bore and being provided with transverse slots, a bushing disposed in said bore, wheels or rings disposed in said transverse slots and 10 arranged to rotate on said bushing, said wheels being countersunk beneath the outer surface of said body portion, a reinforcing casing arranged to slip over said body portion, said casing, said body portion and said 15 bushing having registering openings, a shackle having ends provided with openings arranged to enter said registering openings, and a pin adapted to pass through the openings in the ends of said shackle and 20 into the interior of the bushing for holding said shackle in position when said rings are in predetermined positions. 2. A combination padlock comprising a body portion provided with a central bore 25 and having a longitudinal slot adjacent to said bore and transverse slots, a bushing disposed in said central bore, a plurality of rings rotatably disposed on said bushing, a protective casing slidably disposed on said 30 body portion and having slots arranged to register with certain slots in said body portion, a shackle having ends provided with openings arranged to enter the registering slots of said casing and said body portion, 35 and a pin adapted to pass through the ends of the shackle and to be held in locked position by the engagement of said rings. 3. A combination padlock comprising a body portion provided with a central bore 40 and having a longitudinal slot adjacent to said bore and transverse slots, said body portion having an extension, a bushing disposed in said central bore, a plurality of rings rotatably disposed on said bushing, a 45 protective casing slidably disposed on said body portion and having a slot arranged to receive the extension, and other slots arranged to register with certain slots in said body portion, a shackle having ends provided 50 with openings arranged to enter the registering slots of said casing and said body portion, and a pin adapted to pass through the ends of the shackle and to be held in locked position by the engagement of said 55 rings. 4. A combination padlock comprising a body portion having a central bore and being provided with transverse slots, a bushing arranged to enter said central bore, said 60 bushing being closed at one end, a plurality of rings rotatably mounted on said bushing in said transverse slots, said bushing, said body portion, and each of said rings having slots arranged to register, a pin adapted to enter the interior of said bushing and be- 65 enter the interior of said bushing and be- 70 ing provided with a key adapted to enter the registering slots and being provided with slots arranged to register with said rings, a shackle having ends arranged to pass through said body portion and said bushing, the ends of the shackle being provided with 75 openings arranged to receive said pin, and a reinforcing casing arranged to slip over said body portion and to be locked in position by said shackle. 5. A combination padlock comprising a body portion having a central bore and being provided with transverse slots, a bushing arranged to enter said central bore, said bushing being closed at one end, a plurality of rings rotatably mounted on said bushing in said transverse slots, said bushing, said body portion, and each of said rings having slots arranged to register, a pin adapted to enter the interior of said bushing and be- 80 provided with a key adapted to enter the registering slots and being provided with slots arranged to register with said rings, a shackle having ends arranged to pass through said body portion and said bushing, the ends of the shackle being provided with 85 openings arranged to receive said pin, and a reinforcing casing arranged to slip over said body portion and to be locked in position by said shackle, said reinforcing casing having an opening for viewing said rings, and a guard movably mounted on said casing and adapted to cover said opening. 6. A combination padlock comprising a body portion having a central bore and being provided with transverse slots, a bushing arranged to enter said central bore, said bushing being closed at one end, a plurality of rings rotatably mounted on said bushing in said transverse slots, said bushing, said body portion, and each of said rings having slots arranged to register, a pin adapted to enter the interior of said bushing and be- 90 provided with a key adapted to enter the registering slots and being provided with slots arranged to register with said rings, a shackle having ends arranged to pass through said body portion and said bushing, the ends of the shackle being provided with 95 openings arranged to receive said pin, and a reinforcing casing arranged to slip over said body portion and to be locked in position by said shackle, said reinforcing casing having an opening for viewing said rings, and a guard movably mounted on said casing and adapted to cover said opening. 7. A combination padlock comprising a body portion having a central bore and being provided with transverse slots, a bushing arranged to enter said central bore, said bushing being closed at one end, a plurality of rings rotatably mounted on said bushing in said transverse slots, said bushing, said body portion, and each of said rings having slots arranged to register, a pin adapted to enter the interior of said bushing and be- 100 provided with a key adapted to enter the registering slots and being provided with slots arranged to register with said rings, a shackle having ends arranged to pass through said body portion and said bushing, the ends of the shackle being provided with 105 openings arranged to receive said pin, and a reinforcing casing arranged to slip over said body portion and to be locked in position by said shackle, said reinforcing casing having an opening for viewing said rings, and a guard movably mounted on said casing and adapted to cover said opening. 8. A combination padlock comprising a body portion having a central bore and being provided with transverse slots, a bushing arranged to enter said central bore, said bushing being closed at one end, a plurality of rings rotatably mounted on said bushing in said transverse slots, said bushing, said body portion, and each of said rings having slots arranged to register, a pin adapted to enter the interior of said bushing and be- 110 provided with a key adapted to enter the registering slots and being provided with slots arranged to register with said rings, a shackle having ends arranged to pass through said body portion and said bushing, the ends of the shackle being provided with 115 openings arranged to receive said pin, and a reinforcing casing arranged to slip over said body portion and to be locked in position by said shackle, said reinforcing casing having an opening for viewing said rings, a guard movably mounted on said casing and adapt- 120 ed to cover said opening, and springs disposed between the adjacent wheels and for preventing undue movement thereof. 9. A combination padlock comprising a body portion having a central bore and being provided with transverse slots, a bushing arranged to enter said central bore, said bushing being closed at one end, a plurality of rings rotatably mounted on said bushing in said transverse slots, said bushing, said body portion, and each of said rings having slots arranged to register, a pin adapted to enter the interior of said bushing and be- 125 provided with a key adapted to enter the registering slots and being provided with slots arranged to register with said rings, a shackle having ends arranged to pass through said body portion and said bushing, the ends of the shackle being provided with 130 openings arranged to receive said pin, and a reinforcing casing arranged to slip over said body portion and to be locked in position by said shackle.

said body portion, and each of said rings having slots arranged to register, a pin adapted to enter the interior of said bushing and being provided with a key adapted to enter the registering slots and being provided with slots arranged to register with said rings, a shackle having ends arranged to pass through said body portion and said bushing, the ends of the shackle being provided with openings arranged to receive said pin, a reinforcing casing arranged to slip over said body portion and to be locked in position by said shackle, said reinforcing casing having an opening for viewing said rings, a guard movably mounted on said casing and adapted to cover said opening, springs disposed between the adjacent wheels and for preventing undue movement thereof, and a click connected with each ring for audibly determining the movement of said ring.

8. A combination padlock comprising a body portion provided with a central bore and having a longitudinal slot adjacent to said bore and transverse slots, said body portion having an extension, a bushing disposed in said central bore, a plurality of rings rotatably disposed on said bushing, a protective casing slidably disposed on said body portion and having a slot arranged to receive the extension, and other slots arranged to register with certain slots in said body portion, a shackle having ends provided

with openings arranged to enter the registering slots of said casing and said body portion, and a pin adapted to pass through the ends of the shackle and to be held in locked position by the engagement of said rings, said casing having an opening for exposing a portion of said rings, whereby the latter may be turned to various positions at will.

9. A combination padlock comprising a body portion provided with a central bore and having a longitudinal slot adjacent to said bore and transverse slots, said body portion having an extension, a bushing disposed in said central bore, a plurality of rings rotatably disposed on said bushing, a protective casing slidably disposed on said body portion and having a slot arranged to receive the extension, and other slots arranged to register with certain slots in said body portion, a shackle having ends provided with openings arranged to enter the registering slots of said casing and said body portion, a pin adapted to pass through the ends of the shackle and to be held in locked position by the engagement of said rings, said casing having an opening for exposing a portion of said rings, whereby the latter may be turned to various positions at will, and a shield slidably disposed on said casing and adapted to cover the opening therein.

WILLIAM S. MCADOO.
